Primary Examiner — Mitchell I. Siegel

(74) Attorney, Agent, or Firm — Tillman Wright, PLLC;
James D. Wright; David R. Higgins(57) **CLAIM**

The ornamental design for a ball launcher, as shown and described.

DESCRIPTION

FIG. 1 is a front perspective view of a new design for a ball launcher;

FIG. 2 is a top rear isometric view of the ball launcher of FIG. 1;

FIG. 3 is a front view of the ball launcher of FIG. 1;

FIG. 4 is a left side view of the ball launcher of FIG. 1;

FIG. 5 is a right side view of the ball launcher of FIG. 1;

FIG. 6 is a top view of the ball launcher of FIG. 1;

FIG. 7 is a bottom view of the ball launcher of FIG. 1; and,

FIG. 8 is a rear view of the ball launcher of FIG. 1.
